UNITED STATES PATENT OFFICE.

MICHAEL WAGNER, OF PITTSBURGH, PENNSYLVANIA, ASSIGNOR OF ONE-THIRD TO LOUIS BROIDA AND ONE-THIRD TO ISIDOR WEINBERG, BOTH OF PITTSBURGH, PENNSYLVANIA.

PUMP-VALVE.

1,379,492.

Specification of Letters Patent.

Patented May 24, 1921.

Application filed July 28, 1919. Serial No. 313,773.

To all whom it may concern:

Be it known that I, MICHAEL WAGNER, a citizen of the United States, residing at Pittsburgh, in the county of Allegheny and State of Pennsylvania, have invented certain new and useful Improvements in Pump-Valves, of which the following is a specification.

My invention consists of an improvement in pumps, and especially in the valve mechanism thereof. The object in view is to provide, in a one or more cylinder single, double or triple acting plunger pump, a simple, effective and durable valve construction adapted to perform its functions and to operate in the manner more fully hereinafter described.

In the drawings showing one preferred form of the invention,

20 Figure 1 is a vertical central sectional view of a pump provided with my improved valve;

25 Fig. 2 is an enlarged sectional detail view showing the valve in upward movement and the air circulation to the plunger chamber;

Fig. 3 is a similar view showing the valve seated for operation; and

30 Fig. 4 is a sectional detail view showing a modified construction of packing washer or cup.

In the drawings, the pump cylinder 2 is a cylindrical casing of usual form commonly made for the purpose of pumping automobile tires or the like provided with a supporting base 3 with which the pump casing or barrel is fixedly connected, as by screw threads 4. The central portion of the base 3 is provided with an air inlet chamber 5 communicating through port 6 and a hose or other suitable connection with a tire or other receiver for compressed air.

40 The active element of the pump is the plunger rod 7 extending upwardly through cap 8 and provided with the terminal handle or lever 9 of any suitable construction. Cap 8 may be provided with a stuffing box, if necessary.

45 The plunger valve is composed of a disk 10 fixedly connected with plunger rod 7 in any suitable manner, as by screw threads 11, the plunger rod being preferably shouldered, as indicated at 12, whereby to provide for a good bracing bearing on compressing

movement. Beyond shoulder 12, the spindle 55 13, to which disk 10 is secured, extends a sufficient distance to provide for the loose mounting of the valve cup or washer 14, the periphery of which is deflected as indicated at 14. Washer 15 is of any suitable flexible 60 material, as leather, rubber, or the like, and is sufficiently heavy and stiff to substantially maintain its form and to be expanded against the interior of the casing 2 by the interior compressed air pressure, on downward movement, as in Fig. 3.

It is provided with a central air circulation opening 16 around stem 13 of ample size to permit of free circulation of the air on upward movement of the plunger, and 70 is mounted on stem 13 with sufficient range of vertical movement to allow for free passage of the air between the inner face of disk 10 and washer 15, as in Fig. 2. For the purpose of retaining the washer in operative position and to provide for free upward air circulation on the suction stroke and for upward seating movement on downward travel, the lower side of the washer 14 is spaced away from disk 10 and rests 80 upon a limiting abutment of any suitable kind, as a cotter pin 17 extending through the lower end of stud 13.

By this construction, the washer 14 may drop or disk 10 may be raised the desired 85 distance to provide for ample air circulation and upward movement, and the washer will promptly seat against the under side of disk 10 on downward movement, as in Fig. 3, 90 for compression, such seating being facilitated by recessing the middle under portion of disk 10 as at 19. The annular edge of the deflected periphery 15 binds with practically air tight engagement against the inner wall of casing 2 at all times, and it is not necessary to make the washer of sufficient flexibility 95 to allow for any air circulation at all between its outer edge and the inner edge of the casing. This feature of the invention contributes greatly to its durability 100 while the air supply opening in the middle of the washer insures an ample volume of air at each reverse movement of the pump, so that its capacity is thereby maintained at a maximum at all times.

105 In Fig. 4 I show a modified construction of the washer 14^a in which the central enlarged circulation air space 16^a is provided

within the interior of a reinforcing strengthening and bearing collar 18^a riveted or otherwise secured to the washer, as clearly shown. In such case, the collar 18^a will partially occupy the recess 19 at the central under side of disk 10, and with either construction of washer, the recess 19 facilitates the flat seating of the washer on the under side of the disk.

- 10 It will be understood that the pump and valve may be variously changed in proportions, design, or otherwise by the skilled mechanic, and that the valve construction may be adapted to any suitable type of 15 pump, but that all such changes are to be understood as within the scope of the following claim.

What I claim is:—

In a pump, the combination with a pump barrel, of a plunger having a substantially central recess, and a sealing washer loosely mounted on the plunger and movable to and from a seating position thereagainst, the peripheral portion of the washer co-operating with the barrel and said washer having a substantially central circulation opening of less diameter than the recess of the plunger, the inner margin of said sealing washer overlapping the said recess.

In testimony whereof I hereunto affix my signature.

MICHAEL WAGNER.
